AXIAL FLOW TURBO COMPRESSOR

Curt Keller, Zurich, Switzerland, assignor to
 Escher Wyss Maschinenfabriken Aktiengesell-
 schaft, Zurich, Switzerland, a corporation of
 Switzerland

Application September 21, 1937, Serial No. 164,954
 In Switzerland October 26, 1936

6 Claims. (Cl. 230—119)

This invention relates to multistage axial flow turbo-compressors with one or more casings and at least one external intermediate cooler. The principal object of the invention is to permit the use of intermediate coolers with axial flow turbo-compressors without the energy losses which have heretofore been inherent in such an arrangement.

It has long been considered desirable to operate gas compressors in such manner as to obtain so nearly as possible an isothermal compression, for the reason that under certain pressure conditions the energy absorbed by the compressor is then a minimum. The familiar mode of securing the desired result is to use intermediate coolers either between successive single stages or between successive groups of stages. By increasing the number of intermediate coolers, an isothermal compression can be closely approached, but there is an economic limit to the number of intercoolers because of energy losses at the inlet and outlet of the coolers, as well as throughout the connections to and from the coolers.

The problem is particularly difficult in a multistage axial flow turbo-compressor, because in passing from a stage or group of stages to the intercooler, the direction of flow must change from axial to substantially radial. Such deflection can be effected by the use of curved ducts or casings, but this solution of the problem is attended by the disadvantage that much valuable space is consumed. Furthermore, there are serious energy losses because in an axial flow compressor the velocities of flow are high as compared with the peripheral velocity of the wheel.

The present invention overcomes the above difficulty by causing the stage or group of stages of the axial flow turbo-compressor to deliver to an auxiliary centrifugal wheel deflecting the axial through-flow into the supply conduit leading to the intermediate cooler. Thus, the change in direction of flow takes place with the performance of work by the auxiliary centrifugal wheel, but only to the extent as is necessary for a deflection in the small possible space.

The auxiliary wheel imparts a rotary motion to the medium undergoing compression, such rotary motion occurring in a plane which is normal or approximately normal to the axis of the compressor shaft. This rotary motion is partially converted into pressure in the conduit leading to the intermediate cooler, such conduit being suitably designed for the purpose, as a special casing acting as a diffuser. Since the auxiliary centrifugal wheel receives the medium from the preceding axial flow stages at a high inlet velocity, the auxiliary wheel operates with good efficiency so that the transition from the axial flow compressor to the intermediate cooler occurs with little or no energy loss. Consequently, the in-

vention not only economizes space as compared to the prior art, but reduces the energy losses to a very small amount.

It is recognized that multistage turbo-compressors made up of axial flow and radial flow wheels, either in one or separate casings are known. These prior art devices however had nothing to do with inter-cooling, but usually sought to take advantage of the superiority of the axial flow wheels in the ranges in which the pressures were low and the volumes large, while securing the advantages of the radial flow wheels in the high pressure range, i. e., in that range in which the density of the medium was relatively great. This construction is known to afford economy of space, particularly because the axial stages do not require any room for large radial diffusers. Such construction involves no recognition of the problem of the intercooler, with which device the medium must pass outside the casing of the compressors to the intercooler and then be returned to the casing.

It has also been proposed to use axial and radial flow stages in alternation, but here the purpose was to secure a shifting or even an elimination of the so-called "surging limit". In contradistinction to this, the object of the present invention is, in combination with intermediate coolers only, to obtain, in the smallest amount of space, by means of interposed auxiliary centrifugal wheels, a deflection of working medium into the coolers free from energy losses and even with a recovery of kinetic energy. The effect of the invention, therefore, is to adapt the axial flow type of turbo-compressors to economical operation with intermediate coolers.

Preferred embodiments of the invention are shown in the accompanying drawings, in which—

Fig. 1 is a view, part in elevation and part in longitudinal section, of an axial flow turbo-compressor, having a single casing and having two intermediate coolers with associated radial flow wheels.

Fig. 2 is a section on the line 2—2 of Fig. 1.

Fig. 3 is an end view of the compressor of Fig. 1 as viewed from the left in that figure.

Fig. 4 is a view similar to Fig. 1 and showing a modification in which separate casings are used for different groups of stages.

Fig. 5 is a view similar to the right hand portion of Fig. 4 and showing a possible further modification in which instead of a strictly radial wheel an oblique flow type of wheel is used, the purpose of this view being to indicate that strictly radial flow is not necessary to the attainment of the beneficial results of the invention.

Refer first to Figs. 1-3. The two part housing of a turbo-compressor is indicated at 6 and 7, the runner at 8. The runner is driven by a motor 9 through shaft 11 and carries blades 12, 60

or the equivalent, which turn between stationary guide blades 13 or the equivalent in the housing, the guides 13 and blades 12 being designed for axial flow. The inlet or suction connection is indicated at 14 and the discharge or pressure connection at 15.

Contrary to the usual construction the blades just mentioned are divided into three groups A, B and C by the interposition of radial flow, i. e., 10 centrifugal runners 16 and 17 with associated diffuser housings 18 and 19. These are identical except that they differ in dimensions to correspond to the different stages of compression.

The auxiliary centrifugal wheel 16 receives 15 from group A and deflects the axial through-flow into the spiral diffuser housing 18 which delivers through duct 21 to the conventional multi-tubular cooler 22, in which the compressed gas flows through the tubes and cooling fluid (water) 20 flows around the tubes. Water connections are shown at 23, 24. From intercooler 22 the cooled gas flows by curving pipe 25 to the inlet ring 26 of group B.

The auxiliary centrifugal wheel 17 receives 25 compressed gas from group B and deflects the axial through-flow into the spiral diffuser housing 19 which delivers through duct 27 to intercooler 28 (identical with cooler 22). From cooler 28 flow is by pipe 29 to the inlet ring 31 of 30 group C.

In this way a compact and highly efficient structure is provided. The auxiliary radial flow wheels 16, 17 provide for the necessary deflection of the axial through-flow in a very small space 35 and with the smallest possible loss. Since the centrifugal wheels 16 and 17 impart rotary movement to the gas undergoing compression, the housings 18 and 19 are designed for at least a part of their extent as spiral casings serving as 40 diffusers.

If desired conventional diffusers may be interposed between the periphery of the radial flow wheels 16, 17, and the spiral housings 18, 19, respectively.

45 Such a scheme is shown in Fig. 4 in which diffusers 32 and 33 are indicated at the entrance to housings 18a and 19a. Otherwise, Fig. 4 differs from Fig. 1 only in that the group A stages (runner 8a) are in one housing 6a, 1a, and the 50 groups B and C stages (runner 8b) are in a separate housing 6b, 1b. Other parts corresponding to parts in Fig. 1 are given the same reference numbers with the letter a.

Fig. 5 shows a unit identical with the right 55 hand unit in Fig. 4 except that the wheel 16c, unlike the wheel 16a of Fig. 4, is arranged for oblique and not strictly radial flow and there are no diffusers such as 32, the diffusing function being performed by the housing 18c which is 60 essentially similar to housing 18 of Fig. 1 but is designed to receive the oblique discharge. This structure is shown to indicate that the desired action can be had without adherence to the use of strictly radial wheels for diverting and controlling flow through the intercoolers.

Several modifications have been described for 65 illustrative purposes and others are possible within the scope of the invention.

What is claimed is—
70 1. A turbo-compressor comprising two groups of axial flow stages; an intercooler for cooling compressed working medium; a radial flow wheel coaxial with said turbo-compressor between said groups and arranged to receive working medium

compressed in the first group and deliver it with change of direction to said intercooler with performance of work approximately to the extent necessary for deflection; and a connection for conducting working medium from the intercooler 5 to said second group.

2. A turbo-compressor comprising two groups of axial flow stages; an intercooler for cooling compressed working medium; a radial flow unit arranged coaxially with said axial flow stages and 10 so as to receive medium compressed by the first group of stages, said radial unit including a radial flow wheel and coacting spiral casing arranged to act as a diffuser and deliver medium leaving the radial wheel to the intercooler, the wheel 15 and casing being so designed that the change in direction which occurs in these parts is effected with performance of work approximately to the extent necessary for the deflection; and a connection for conducting working medium from 20 the intercooler to the said second group of stages.

3. The combination of a multi-stage axial flow turbo-compressor including a housing and a runner, and having at least one intercooler interposed between two successive stages; and a radial flow 25 wheel turning with said runner within said housing, the radial flow wheel being so designed as to receive medium from the first of said successive stages, deflect it from its axial path, and deliver it to said intercooler with performance of 30 work approximately to the extent necessary for deflection.

4. The combination of a multi-stage axial flow turbo-compressor including a housing and a runner, and having at least one intercooler interposed between two successive stages; and a flow diverting unit comprising a radial flow wheel turning with said runner within a portion of said housing formed as a diffuser, the parts being so designed that the radial flow wheel receives working 40 medium from the first of said successive stages, and deflects it through said diffuser to said intercooler with performance of work approximately to the extent necessary for deflection.

5. The combination of a multi-stage axial flow 45 turbo-compressor including a housing and a runner and having at least one intercooler interposed between two successive stages; and means for guiding working medium flowing from the first of said successive stages from its axial path to 50 said intercooler without substantial loss of energy, said means comprising a radial flow wheel turning coaxially with said runner, and so designed as to perform substantially the minimum work consistent with efficient deflection of 55 the working medium from its axial path.

6. The combination of a multi-stage axial flow turbo-compressor including a housing and a runner and having at least one intercooler interposed between two successive stages; and means 60 for guiding working medium flowing from the first of said successive stages from its axial path to said intercooler without substantial loss of energy, said means comprising a radial flow wheel turning coaxially with said runner, and a housing 65 for said radial flow wheel, said housing serving as a diffuser to convert velocity head of medium leaving the radial wheel into pressure as the medium approaches the intercooler, and the radial flow wheel being so designed as to perform 70 substantially the minimum work consistent with effective deflection of the working medium from its axial path.
